(57) **CLAIM**

The ornamental design for a mop component for a robotic vacuum cleaner, as shown and described.

DESCRIPTION

1. Mop component for a robotic vacuum cleaner

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

Reproductions. 1.1-1.10 show a mop component for a robotic vacuum cleaner; the product is used for a cleaning device, such as a robotic vacuum cleaner.

1 Claim, 10 Drawing Sheets
